UNITED STATES PATENT OFFICE.

CHARLES H. GREENWOOD, OF CANTON, OHIO.

BOBBIN CASE.

Application filed March 5, 1924. Serial No. 697,081.

This invention relates to sewing machines and more particularly to improvements in the bobbin cases and rotary loop taker.

The objects of the invention are to provide a bobbin case and rotary hook of such construction that the bobbin may be placed either end up in the bobbin case, without affecting the tension upon the lower thread; to provide means for causing a self threading of the lower or bobbin thread through the tension upon the bobbin case; to provide means for preventing rotation of the bobbin case without pinching the thread; to provide a two-part bobbin case having an annular groove at the meeting edges of the parts to receive the rotary loop taker, and to generally improve and simplify mechanism of this character.

The above and other objects may be attained by constructing the device in the manner illustrated in the accompanying drawing, in which—

Figure 1 is a plan sectional view of a portion of a sewing machine, showing the improved bobbin case and loop taker;

Fig. 2, a vertical, sectional view of the same;

Fig. 3, a plan view of the sliding plate, which prevents rotation of the bobbin case;

Fig. 4, a plan view of the lower member of the bobbin case;

Fig. 5, an edge elevation of the same;

Fig. 6, a plan view of the upper member of the bobbin case;

Fig. 7, a section on the line 7—7, Fig. 6;

Fig. 8, a side elevation of the upper member;

Fig. 9, a section on the line 9—9, Fig. 10; and

Fig. 10, a section on the line 10—10, Fig. 9.

Similar numerals refer to similar parts throughout the drawing.

A portion of the base plate of a sewing machine is shown at 1 provided with the depending wall 2, through which the shaft 3 is journaled, a gear 4 being fixed upon the extremity of said shaft. A bracket 6 is spaced from the wall 2 as by the lugs 7 and 8 and connected thereto as by the screws 9.

A bevel pinion 10 is mounted upon the lower end of the spindle 11 of the rotary loop taker 12, said pinion meshing with the gear 4. The spindle 11 of the rotary loop taker

65 is journaled in a vertical bearing 13 formed

in the bracket 6 and may be lubricated through the passage 14 communicating with the oil reservoir 15 provided in said bracket.

An eccentric 16 is fixed upon the spindle 11, just above the bracket 6, and is received in an elongated opening 17, formed in the central portion of the sliding plate 18. This plate is provided at each end with a slot 19 through which is located a screw or the like 20, secured in the bracket 6, permitting a longitudinal reciprocating movement of the plate.

A pair of aligned, inwardly curved fingers 21, are provided upon the upper face of the plate 18, one upon each side of the central opening 17 thereof.

The body portion 12 of the loop taker is of annular shape provided at its upper edge with an inturned annular flange 23 having a cut-out extending substantially one-fourth 75 of the way around the same, terminating at one end in the inwardly directed loop seizing hook 24.

The bobbin case is formed of two parts, the lower part comprising the supporting 80 plate 25 having the annular shoulder 26 arranged to engage the annular flange 23 upon the loop taker and provided with the radial notch 27.

The thread case 28 comprises a cylinder 85 preferably formed upon the lower portion 25 of the bobbin case and of sufficient height and diameter to receive the usual round bobbin and has an inwardly disposed, annular flange 29 at its lower end to support the bobbin.

A radial slot 30 is provided in the thread case in radial alignment with the notch 27, an enlarged, radial shoulder 31 being formed upon the thread case, forming a continuation 95 of one side of said slot.

A leaf spring 32 is fixed as at 33 to the thread case and has the outturned end 34 arranged to engage the shoulder 31 in alignment with the slot 30. The upper face of the shoulder 31 is beveled, as best shown in Fig. 5.

The upper member 35 of the bobbin case is substantially conical and provided with the eccentric opening 36 of a size and shape to receive the thread case 28. A curved cut-out portion 37 is provided to accommodate the spring 32 and a notch 27 corresponding with the notch 27 of the lower member.

A pair of aligned notches 38 are provided,

one upon each side of the opening 36, for the purpose of receiving the fingers, as will be further described.

In assembling the bobbin case, the lower member is inserted in the rotary loop taker beneath the flange 23, and the upper member placed thereover, the edge thereof resting upon the flange 23.

Screws 39 are then inserted through the apertures 40 and 41 in the lower and upper members, securing the two parts of the bobbin case together and holding the same in assembled condition upon the loop taker, which is thus permitted to rotate with reference thereto.

In operation, the bobbin may be placed in the bobbin case in either position and the loose end of the thread from the bobbin will be taken up by the needle loop as the same passes around the bobbin case, pulling the bobbin thread through the slot 30 and between the shoulder 31 and the tension spring 32, and directing the extremity of the same toward the tube 22 which registers with the needle opening in the needle plate 42.

As the spindle 11 revolves, the eccentric 16 revolving therewith, will reciprocate the plate 18, always holding one of the fingers 21 in engagement with the adjacent notch 38 of the bobbin case, preventing rotation of the same and permitting the needle loop to pass around the bobbin case, the motion being so timed that each finger 21 moves out of engagement with its notch as the needle loop passes the same.

From the above, it will be obvious that a simple and efficient bobbin case is provided in which the bobbin may be placed either end up in the case, without affecting the tension upon the lower thread and in which a two-part bobbin case is provided which may be easily and readily inserted into the rotary loop taker and held in assembled position therein; and in which simple and efficient means are provided for preventing rotation of the bobbin case without pinching of the thread.

I claim:—

1. In a sewing machine, a rotary loop taker, a bobbin case peripherally supported thereon

and provided with notches and a sliding plate provided with fingers arranged to alternately engage the notches to positively prevent rotation of the bobbin case without retarding the loop.

2. In a sewing machine, a rotary loop taker, a bobbin case peripherally supported thereon and provided with a slot, and a tension device upon the bobbin case comprising a radial shoulder and a leaf spring adjacent to the slot arranged to guide the thread radially away from the bobbin directly toward the path of the needle.

3. In a sewing machine, a rotary loop taker, a bobbin case peripherally supported thereon and provided with a slot, and a tension device upon the bobbin case comprising a radial shoulder and a leaf spring adjacent to said slot, arranged to automatically thread through the action of the needle loop.

4. In a sewing machine, a horizontal rotary loop taker, a bobbin case peripherally supported thereon and provided with a radial slot, and a tension device upon the bobbin case adjacent to the slot, comprising a radial shoulder aligned with one side of the slot, and a leaf spring engaging the radial face of said shoulder to guide the thread radially toward the path of the needle.

5. In a sewing machine, a rotary loop taker provided with an annular inturned flange having a cut-out extending around substantially one-fourth of its circumference, a thread seizing hook at one extremity of said flange the other extremity of the flange being beveled in the opposite direction from the hook and a bobbin case provided with an annular groove which receives the annular flange of the loop taker.

6. In a sewing machine, a rotary loop taker provided with a spindle, an eccentric fixed upon the spindle, a sliding plate operated by the eccentric and provided with a pair of fingers, and a bobbin case mounted in the loop taker and having notches arranged to be alternately engaged by said fingers.

In testimony that I claim the above I have hereunto subscribed my name.

CHARLES H. GREENWOOD.
